GAME BOARD

Ernest T. Frisk, Hibbing, Minn.

Application July 16, 1959, Serial No. 56,804

Term of patent 14 years

(Cl. D34—5)

FIG. 1

FIG. 2

FIG. 3

Fig. 1 is a perspective view of a game board, showing my new design;

Fig. 2 is a cross section taken along line 2—2 of Fig. 1; and

Fig. 3 is a cross section taken along line 3—3 of Fig. 1.

The dominant feature of my design resides in the portion shown in full lines.

I claim:

The ornamental design for a game board, as shown and described.
